UNITED STATES PATENT OFFICE

2,168,810

CHAIR BASE

Henry W. Sheldrick, Gardner, Mass., assignor to
 Collier-Keyworth Company, Gardner, Mass., a
 corporation of Massachusetts

Application January 12, 1938, Serial No. 184,633

2 Claims. (Cl. 155—138)

This invention relates to chair bases of the type commonly employed for office chairs where-in the base is provided with a hub for supporting the chair spindle and legs radiating from the hub. Heretofore, particularly where a metal hub and wood legs have been employed, much difficulty has been experienced from a development of lost motion between the spindle-carrying sleeve or hub and the legs, and this in spite 10 of the use of wood filler blocks between adjacent legs at the hub. The chief object of this invention is to prevent this difficulty, and in general the invention relates to a method of securing the metal hub parts together in such a 15 manner that this lost motion is prevented.

For a more complete understanding of this invention, reference may be had to the accompanying drawing, in which

Figure 1 is a perspective view of the metal portion of a chair hub made in accordance with this invention.

Figures 2 and 3 are horizontal sections through the chair hub on section lines 2—2 and 3—3, respectively, but showing portions of the legs and 25 filler blocks in position.

Figure 4 is a vertical section through the metal portion of the hub on line 4—4 of Figure 2.

Referring to the drawing, at 1 is indicated a tubular member for receiving the spindle (not shown) of the chair iron in the usual manner. This tube 1 has secured thereto near its upper end a plate 2 which is shown as provided with a central bore portion 3 about which the metal is dished upwardly, this dished portion being held 35 between an annular rib 4 projecting outwardly from the tube 1 and a flanged ring member 5 secured in position by the outwardly flared upper end 6 of the tube 1. Arranged around the axis of the tube 1 are a series of leg-receiving 40 sockets 10, each socket being formed channel-shaped in cross section with the sides of the channel inclined toward each other as at 11, thus forming an outwardly tapered opening to receive the matingly tapered end portion 12 of the chair leg 13. Not only is each socket 10 tapered outwardly, but it is also tapered upwardly, its narrower end being positioned at its top so that the weight of the chair and of the occupant tends to tighten the legs in the sockets. The upper 45 edges of the side walls 11 are shown as extended as at 14 through openings 15 in the plate or disk 2, these extensions being riveted over as at 16 on the top of the plate 2 so as to secure the upper ends of the sockets firmly in position. The 50 lower ends of the socket members are provided

with extensions 20 from their central web portions 21 and these extensions are clamped in position against the outer face of the tube 1 as by means of a clamping collar 25 which is retained on the lower end portion of the tube 1 by spinning or otherwise forming an outwardly directed flange 26 thereon. The parts are so disposed, however, that when the ring 25 is in position, not only are the extensions 20 firmly clamped to the outer face of the tube 1, but the adjacent apices 27 between the webs 21 and the sides 11 of the sockets are each forced into tight engagement with the adjacent lower apex of the neighboring socket. Between the legs 13 carried by the socket members may be placed 15 the filler blocks such, for example, as those shown at 30 in Figures 2 and 3. It has been found in practice that filler blocks alone do not prevent the working loose of the leg members due to shrinkage of the wood parts or otherwise, 20 but by forcing the lower ends of the socket members into tight engagement with each other at their lower ends, it has been found that this liability of the leg members to develop play with 25 relation to the hub member is effectively prevented so long as the leg members tightly engage in the socket members, even without the use of the filler blocks 30 which may, however, be employed in order to improve the appearance 30 of the chair base and to cover the metallic portions thereof, except at the top and lower face of the chair base. A metal cover plate screwed to the lower faces of the legs and bridging the 35 filler blocks such as is commonly employed but which is not shown herein, may be used if desired, as an additional means of securement of the parts together. By the construction heretofore described, the socket members are firmly held in position at their upper ends by the riveting over of the extensions 14 in the top plate 2 and at 40 their lower edge by the forcing of adjacent socket members against each other and against the outer face of the tube 1 under stress.

From the foregoing description of one embodiment of this invention, it should be evident to 45 those skilled in the art that various other changes and modifications might be made without departing from the spirit or scope of this invention as defined by the appended claims.

I claim:

1. A chair base comprising a tubular member, a plurality of channel shaped leg-receiving sockets arranged with their webs toward said member and surrounding the same, and means for holding adjacent end portions of said sock- 55

ets forced against each other under stress and secured to said tubular member.

2. A chair base comprising a central tubular member, a plate secured to the upper portion of said member, a plurality of channel shaped leg-receiving sockets arranged about said tubular member and secured at their upper ends to said

plate, said sockets having extensions at their lower ends, and a ring surrounding and clamping said extensions to said tubular member with the lower end of each socket forcibly pressed against the next adjacent sockets.

HENRY W. SHELDRICK.
